UNITED STATES PATENT OFFICE

WILLIAM NELSON PARKES, OF BROOKLYN, NEW YORK, ASSIGNOR TO THE SINGER MANUFACTURING COMPANY, OF ELIZABETH, NEW JERSEY, A CORPORATION OF NEW JERSEY

BOBBIN-RETAINING DEVICE FOR SEWING-MACHINE LOOP TAKERS

Application filed January 15, 1929. Serial No. 332,611.

This invention relates to improvements in rotary loop-takers for sewing machines of the type in which the loop-taker casts needle-thread loops about a thread-carrying bobbin in the formation of lock-stitches, the object of the invention being to provide improved means for latching the lower-thread bobbin within its carrier.

In a preferred embodiment of the invention, the present improved bobbin-latching device has been applied to a sewing machine loop-taker of the vertical-axis type, in which the bobbin-carrier is provided with a peripheral bearing-rib journaled in a loop-taker raceway. The bobbin-carrier is open at its top and has at its bottom a narrow flange projecting inwardly from the side wall of the carrier, upon which flange the bobbin is supported. Upon its upper rim, the bobbin-carrier is provided with shoulders engageable with stationary stop-elements to limit movement of the carrier to slight oscillations about the loop-taker axis.

Attached to the outer wall of the bobbin-carrier, below its bearing rib, is a retainer-member having diverging apertured ears through which are passed its securing screws. Extending upwardly from between said ears is a spring-tongue, which passes through a slot in the wall of the bobbin-carrier adjacent its bearing-rib and into a clearance recess in the inner wall of the bobbin-carrier. The tongue terminates at its free end in a lip overhanging the outer edge of the upper bobbin-flange, said lip being preferably protected against snagging the needle-thread loop by a flange upon the upper edge of the bobbin-carrier. This lip is shaped to be deflected toward the outer side of the bobbin-carrier by the act of inserting or removing a bobbin, the spring-tongue and the clearance-recess in the bobbin-carrier permitting this movement of the lip.

In the accompanying drawings, Fig. 1 is a top-plan view of a portion of a sewing machine cloth-plate, with the slide-plates removed to expose the loop-taker containing the present improvement. Fig. 2 is a sectional view substantially on the line 2—2, Fig. 1. Fig. 3 is a view in side elevation of

the bobbin-carrier on the bobbin-latch side thereof. Fig. 4 is a perspective view of the bobbin-carrier. Certain features of this loop-taker mechanism are shown more in detail in an application filed January 15, 1929, with Serial No. 332,610.

Referring to the drawings, the present improvement is shown as embodied in a sewing machine having a cloth-plate 1, upon which is secured a throat-plate 2 by means of screws, as 3. The throat-plate is provided with the usual needle-aperture 4 and with parallel slots, as 5, through which slots the feed-dog 6, of the lower four-motion type, is projected to intermittently advance the work.

Disposed directly below the plane of the under side of the throat-plate is a loop-taker of the vertical-axis type, comprising an outer body 7 separably secured upon an inner body 8. The loop-taker bodies are provided at their upper rims with inwardly directed flanges 9 and 10 suitably spaced to form a raceway for a bearing-rib 11 upon the outer periphery of a bobbin-carrier 12, which is therefore journaled in the loop-taker. The outer body 7 of the loop-taker is provided with a beak 13 for seizing the needle-thread loop and with an oppositely directed heel or spur 14 upon which the needle-thread loop is discharged by the beak 13 and by which said loop is held until just before the setting of the stitch.

The bobbin-carrier 12 is open at its top and is substantially bottomless, its base comprising a narrow internal flange 15 for supporting a bobbin 16 disposed within the bobbin-carrier. Extending outwardly and upwardly from the bobbin-carrier base is an auxiliary hook 17 disposed between the inner loop-taker body and the bobbin-carrier, said hook 17 acting to direct toward the bottom of the bobbin-carrier a limb of the needle-thread loop seized by the loop-taker, which limb is initially detained by a nose 18, formed upon the bearing-rib 11 by interrupting its continuity.

The bobbin 16 is latched against accidental upward movement out of its carrier during the sewing operation, the latching mean

comprising a retainer-member having a spring-tongue 19, of which the upper free end is reversely bent to provide a V-shaped lip 20, having its apex directed toward the bobbin-axis and overhanging the outer edge only of the upper side of the bobbin. The inclined upper and under sides of the lip 20 provide for readily deflecting the tongue 19 outwardly by the action thereupon of a bobbin when manually inserting or removing the same.

The tongue 19 extends upwardly from a base-member which at opposite sides of the tongue is provided with apertured ears, as 21, for the reception of screws, as 22, whereby the retainer-member base is fastened upon the outer side-wall of the bobbin-carrier below its bearing-rib 11. Intermediate its ends, the tongue 19 extends through a slot 23 provided in the wall of the bobbin-carrier adjacent the bearing-rib 11, while the upper end of the tongue is disposed within a clearance recess 24 formed in the inner side of a flange 25 upon the bobbin-carrier above the bearing-rib 11. The flange 25 is preferably sufficiently high to act as a guard for the lip 20 to thereby prevent said lip from snagging the needle-thread loop.

The flange 25 is disposed at the cast-off side of the loop-taker and terminates at opposite ends in stop-shoulders 26 and 27. Adjacent to the shoulder 27, the upper edge of the bobbin-carrier, as at 28, is disposed below the upper bobbin-flange to provide for convenient access to the bobbin for removal. The shoulder 26 of the bobbin-carrier is adapted to engage a stop-lug 29 depending from the throat-plate 2, in order to restrain said bobbin-carrier against rotation with the loop-taker. Movement of the bobbin-carrier in the opposite direction is limited by a stationary stop-finger 30 which is positioned to engage the shoulder 27 of the bobbin-carrier. The referred to stop-elements for the bobbin-carrier are not herein described in detail, as they form the subject of a separate patent application filed January 15, 1929, with Serial No. 332,612.

The bobbin-carrier is oscillated slightly, in a direction opposite to the direction of rotation of the loop-taker, by means of an opener-finger 31 which is positioned to engage a shoulder 32 upon the bobbin-carrier. It may be mentioned that this reverse oscillation of the bobbin-carrier is designed to open a needle-thread loop passage between the stop-shoulder 26 and the stop-lug 29, as well as to pull thread from the bobbin, but this subject-matter forms part of still another patent application filed January 15, 1929, with Serial No. 332,610.

It is to be understood that while the lip 20 of the bobbin-latch or retainer normally overhangs the outer edge of the upper flange 65 of a bobbin within the carrier, said lip is nor-

mally not in contact with the bobbin and merely guards against excessive rising movements of the bobbin within its carrier. The bobbin-thread is passed through a "self-threading" slit 33, beneath a tension-spring 34 secured upon the flange 25, and over the stop-shoulder 26 to the throat-plate needle-aperture.

Having thus set forth the nature of the invention, what I claim herein is:

1. In a sewing machine loop-taker, a bobbin-carrier journaled in said loop-taker having a bobbin cavity, a bobbin positioned in said cavity, and means for confining the bobbin in the cavity of the bobbin-carrier comprising a retainer-member sustained by the bobbin-carrier and having a yielding lip projecting from the bobbin-carrier wall inwardly across an outer edge of the bobbin to an extent slightly within said outer edge.

2. In a sewing machine loop-taker, a bobbin-carrier journaled in said loop-taker, a bobbin disposed within the bobbin-carrier, means for restraining the bobbin-carrier against rotation with the loop-taker, and means for confining said bobbin within the bobbin-carrier comprising a retainer-member secured upon the side wall of the bobbin-carrier and having a yielding lip overhanging the outer edge of the bobbin.

3. In a sewing machine loop-taker of the vertical-axis type having a raceway, an open-top bobbin-carrier having a peripheral bearing-rib journaled in said raceway, a bobbin disposed within the bobbin-carrier, means for restraining the bobbin-carrier against rotation with the loop-taker, and a retainer-member secured upon the outer wall of said bobbin-carrier below its bearing-rib, said retainer-member terminating in a yielding lip overhanging the upper side of said bobbin.

4. In a sewing machine loop-taker, a bobbin-carrier journaled in said loop-taker, a bobbin disposed within the bobbin-carrier, a bobbin-confining lip overhanging the outer edge of the bobbin, and a spring-tongue carrying said lip, the bobbin-carrier having a clearance recess in its inner wall for said tongue.

5. In a sewing machine loop-taker, a bobbin-carrier journaled in said loop-taker, a bobbin disposed within the bobbin-carrier, and a retainer-member sustained by the bobbin-carrier having a lip yieldable across the outer edge of the bobbin, said bobbin-carrier adjacent the lip having a guard for protecting said lip against snagging a thread-loop passed around the bobbin-carrier by said loop-taker.

6. In a sewing machine loop-taker, a bobbin-carrier journaled in said loop-taker having a side wall defining a bobbin-cavity, a bobbin disposed within the bobbin-carrier, and a retainer-member sustained by the bobbin-carrier having a spring-tongue extending

through said side wall of the bobbin-carrier and terminating in a lip overhanging the outer edge of said bobbin.

7. In a sewing machine loop-taker, a bobbin-carrier journaled in said loop-taker, a bobbin disposed within the bobbin-carrier, and means for confining the bobbin within its carrier, comprising a retainer-member having spaced apertured ears secured upon the bobbin-carrier, a spring-tongue projecting from between said ears, and a lip carried by said tongue in position to overhang an edge of the bobbin.

8. In a sewing machine loop-taker of the vertical-axis type, a bobbin-carrier journaled in said loop-taker, a bobbin disposed within the bobbin-carrier, and a retainer-member having a lip yieldable across the outer edge of the bobbin, said bobbin-carrier having a portion of its upper rim disposed below the upper side of the bobbin and an adjacent portion constituting a thread-loop guard for said lip.

In testimony whereof, I have signed my name to this specification.

WILLIAM NELSON PARKES.
